IGNITION DEVICE

Oscar J. Leins, Milwaukee, Wis., assignor to Milwaukee Gas Specialty Company, Milwaukee, Wis., a corporation of Wisconsin

Application April 30, 1930, Serial No. 448,604

9 Claims. (Cl. 158—115)

This invention relates to certain new and useful improvements in ignition devices and refers more particularly to means for igniting hydro-carbon or gas burners and the like from a pilot light, especially where the burners are located remote from the pilot light and beyond the normal reach of the flame projected therefrom.

It is, therefore, an object of this invention to increase the length of a flame projected from a pilot light and thus enable a conventional lighter of the type providing ignition for the cooking section burners of a gas range, to also provide safe ignition for an oven burner and/or any other burner located beyond normal reach of a flame projected from the pilot light.

A more specific object of this invention resides in the provision of an auxiliary fuel supply adapted to feed a flame projected from a pilot light and thereby increase its effective length.

With the above and other objects in view which will appear as the description proceeds, my invention resides in the novel construction, combination and arrangement of parts substantially as hereinafter described and more particularly defined by the appended claims, it being understood that such changes in the precise embodiment of the hereindisclosed invention may be made as come within the scope of the claims.

In the accompanying drawing, I have illustrated one complete example of the physical embodiment of my invention constructed according to the best mode I have so far devised for the practical application of the principles thereof, and in which:

Figure 1 is a top plan view of a portion of a conventional gas range illustrating the application of my invention thereto;

Figure 2 is an enlarged sectional view taken through Figure 1 on the plane of the line 2—2; and

Figure 3 is a transverse sectional view taken through Figure 2 on the plane of the line 3—3.

Referring now more particularly to the accompanying drawing, in which like numerals designate like parts throughout the several views, the numeral 5 represents the oven of a conventional gas range and 6 the cooking section thereof. As is customary, the cooking section has a number of burners 7 which are adapted to be connected with a fuel supply through a stringer pipe 8 upon opening of their respective valves or cocks 9. The oven is provided with a burner 10 of any suitable design which is also adapted to be connected with the stringer pipe upon opening of its associated cock 11.

To provide ignition for the burners 7, a centrally located pilot 12 at which a small pilot flame continually burns, is connected with the stringer pipe 8 through a tube 13 and a valve 14. The valve 14 is of the conventional push button type having a by-pass permitting sufficient fuel to flow to the pilot to maintain the small pilot flame and is adapted upon depression of its push button 15 to suddenly increase the volume of fuel flowing to the pilot to project flames diagonally therefrom toward the various burners.

The specific structure of the pilot is best illustrated in Figures 2 and 3 and includes a substantially T shaped valve casing 16 threaded on the adjacent end of the tube 13. A short stem 17 is threaded into an aperture in the valve casing 16 which communicates with the opening in which the tube 13 is threaded, to receive fuel entering the casing through tube 13 and conduct the same upwardly to a pilot tip 18 which is secured to the upper end of the stem 17.

The tip 18 is of suitable construction depending upon the nature of the fuel and is provided with a plurality of orifices 19 arranged radially in line with the various burners 7 and from which the igniting flames project. As disclosed in my Patent No. 1,747,015, the pilot also includes a hood 20 which is readily detachably connected with a base 21 suitably fixed to the stem 17. The hood 20 has a plurality of openings 22 axially aligned with the orifices 19 to permit the igniting flames to project therefrom.

To supply ignition for the oven burner 10, the pilot tip 18 has an opening 24 in axial alignment therewith to receive and support the adjacent end of a tube 25 into which a flame is projected simultaneously with the projection of the flames toward the burners 7. The opposite end of the tube 25 passes through a suitable opening in the oven wall and terminates adjacent the oven 46 burner.

It is, therefore, apparent that a flame projected into and continuing through the tube 25 will ignite the fuel issuing from the oven burner ports 26, but as a flame projected from the pilot tip 46 18 normally cannot reach the outer end of the tube 25 and the oven burner, means are provided for increasing the effective length of the flame projected into the tube to insure positive and continuous flame travel to the extreme end of the 50 tube.

This means consists of an auxiliary fuel supply, which upon projection of a flame into the tube feeds fuel to the flame. To this end, the valve casing 16 has a port or passageway 27 lead- 55

ing from the opening into which the tube 13 is threaded to the lower end of a substantially vertical bore 28. The bore 28 forms a small well whose upper end is normally closed by a ball 5 check valve 29 received in an enlarged bore 30 projected downwardly from the top of the valve casting in axial alignment with the bore 28. Communicating with the inner end of the bore 30 is a port 31 and an internally threaded opening 32 10 into which one end of a tube 33 is secured. The outer end of the tube 33 is directed upwardly, as at 34, and enters the tube 25 at a point to which the flame projected from the pilot reaches.

The outer end of the bore 30 in the valve casting, 15 is closed by a suitable cap 35 having a threaded central bore in which the screw 36 is adjustably secured to provide a stop engageable with the ball check valve 29 to limit its movement from its seat.

20 During the normal condition of the pilot when but a small flame is burning, the check valve maintains itself seated by gravity and closes off the supply of fuel to the tube 33, but immediately upon depression of the push button 15, to flash 25 the pilot flames, the increased volume of fuel lifts the ball check valve and permits fuel to pass through the tube 33 and into the tube 25 to feed the flame projected therein and thus increase its length sufficiently to extend from the pilot tip 30 to the oven burner.

It is noted that the tube 25 is provided with a longitudinal slot 37 at its bottom. This permits a circulation of air into the tube and insures positive and continuous flame travel through the 35 tube.

From the foregoing description taken in connection with the accompanying drawing, it will be readily apparent to those skilled in the art to which an invention of the character described 40 appertains, that I provide a novel and safe means for igniting a burner or burners located beyond the normal reach of a flame flashed from a pilot light. It is also obvious that this manner of providing ignition is not limited to the gas range 45 oven burners, but may be readily adapted to many other installations such as water heaters and other appliances whose burners are located adjacent to but beyond the normal reach of a flame projected from a pilot light.

What I claim as my invention is:

50 1. In combination with a hydrocarbon burner or the like, an ignition device including a pilot, means for projecting a flame from the pilot towards the burner, means for conducting the flame from the pilot toward the burner, means communicating with said conducting means for conveying auxiliary fuel to the flame intermediate the pilot and the burner, and means responsive to the operation of said flame projecting means for supplying auxiliary fuel to the conducting means.

55 2. In combination with a hydrocarbon burner or the like, an ignition device including a pilot, means to project a flame from said pilot toward the burner, means for conducting the flame from the pilot toward the burner, said flame being of insufficient length to reach the burner, means forming a passageway for conducting auxiliary fuel to said last named means intermediate the pilot and the burner, and valve means responsive to the operation of the first named means for controlling the passage of fuel through the passageway.

60 3. In combination with a hydrocarbon burner or the like, an ignition device including a pilot, means for projecting a flame from the pilot to-

ward the burner, means for conducting the flame toward the burner, and means carried by the pilot and automatically operable upon operation of said flame projecting means for conducting auxiliary fuel to the flame within the conducting 5 means.

4. In combination with a hydrocarbon burner, an ignition device including a pilot, a tubing leading from said pilot to the burner, means to project the flame from said pilot into said tubing 10 and means automatically responsive to the operation of said last named means to supply auxiliary fuel to said flame at a point intermediate the ends of said tubing.

15 5. In combination with a hydrocarbon burner or the like, an ignition device including a gas supply pipe, operable means in said supply pipe to permit a flow of gas therethrough at a low and at a high velocity, a connection at one end of said supply pipe having two branches, a pilot 20 supplied with gas from one branch of said connection and positioned to emit a flash toward the burner upon gas flowing thereto through the supply pipe at the high velocity, a pipe connected to the other branch of said connection and 25 terminating intermediate the pilot and the burner, and means in said other branch automatically operable in response to the flow of gas through said supply pipe at the high velocity to admit gas into said last named pipe, and into the path 30 of the flash to increase the effective length thereof.

6. In combination with a hydrocarbon burner or the like, an ignition device comprising a gas supply pipe, operable means in said supply pipe 35 to permit a flow of gas therethrough at a low and at a high velocity, a connection at one end of said pipe having two branches, a pilot supplied from one branch of said connection and positioned to emit a flash toward the burner upon 40 gas flowing thereto through the supply pipe at the high velocity, a second pipe connected to the other branch of said connection and terminating intermediate the pilot and the burner, a valve in said other branch adapted to be automatically 45 opened in response to the flow of gas to the pilot at the high velocity to admit gas to said second pipe and into the path of said flash, said valve normally being closed to prevent gas from flowing through said second pipe, and means to regulate the degree of opening of said valve to determine the volume of gas flowing through said second pipe.

7. In combination with a hydrocarbon burner or the like, an ignition device comprising, a gas 55 supply pipe, operable means in said supply pipe to permit the flow of gas therethrough at a low and at a high velocity, a connection at one end of said pipe having two branches, a pilot supplied with gas from one branch of said connection and 60 positioned to emit a flash toward said burner upon gas flowing thereto through said supply pipe at the high velocity, a housing for said pilot, a tube leading from said pilot housing to the burner to enclose the flash from the pilot, a second pipe 65 connected to the other branch of said connection and leading into said tube at a point intermediate the pilot and the burner, and means in said other branch automatically operable in response to the flow of gas through said supply pipe at the high 70 velocity to admit gas to said second pipe, and into the path of the flash travelling therein.

8. In combination with a hydrocarbon burner, an ignition device including a gas supply pipe, operable means in said supply pipe to permit a 75

flow of gas therethrough at a low and at a high velocity, a pilot connected with said supply pipe receiving sufficient gas at low velocity to maintain a pilot flame and positioned to project a 5 flame toward the burner upon gas flowing thereto at the high velocity, means to conduct gas from the supply pipe to a point in the path of the projected flame at a distance from the pilot, and means normally shutting off communication 10 between the supply pipe and said means to conduct gas to the flame and automatically operable in response to the flow of gas through the supply pipe at the high velocity to admit gas to said conducting means and into the path of the flame to 15 increase its effective length.

9. In combination with a hydrocarbon burner, an ignition device including a gas supply pipe, operable means in said supply pipe to permit a

flow of gas therethrough at a high and at a low velocity, a pilot tip connected with the supply pipe receiving sufficient gas therefrom at low velocity to normally maintain a small flame thereat and positioned to admit a flash toward the hydrocarbon burner upon gas flowing thereto at the high velocity, means communicated with said supply pipe to conduct gas to a point spaced from the pilot tip and in the path of the projected flash, and a ball valve normally seated by gravity 10 on a valve seat in said conducting means to close the same and adapted to be lifted from the seat to open said conducting means in response to the flow of gas through the supply pipe at high velocity to admit gas to said conducting means 15 and into the path of the flash to increase its effective length.
